UNITED STATES PATENT OFFICE.

HENRIK C. STRÄNG, OF HARVEY, ILLINOIS; A. RUDOLPH GROSSTEPHAN, ADMINISTRATOR OF SAID HENRIK C. STRÄNG, DECEASED, ASSIGNOR TO GEORGE ROEDER, OF HARVEY, ILLINOIS.

INTERNAL-COMBUSTION ENGINE.

1,232,622.

Specification of Letters Patent. Patented July 10, 1917.

Application filed June 19, 1914. Serial No. 846,004.

To all whom it may concern:

Be it known that I, HENRIK C. STRÄNG, a citizen of the United States, and a resident of the town of Harvey, in the county 5 of Cook and State of Illinois, have invented certain new and useful Improvements in Internal-Combustion Engines; and I do hereby declare that the following is a full, clear, and exact description of the same, reference 10 being had to the accompanying drawings, and to the numerals of reference marked thereon, which form a part of this specification.

This invention relates to an improved type 15 of four cycle internal combustion engine wherein noise and vibration are practically obviated, and all of the working parts are positively driven and operate independently of springs. At the present time the most 20 general type of internal combustion engine is that employing puppet valves, and these are objectionable for many reasons, not least among which may be mentioned the noise accompanying their operation, as well as 25 the inefficient closing of the respective passages which they control. In the present invention the use of peculiarly efficient slow moving inlet and exhaust sleeve valves admits a construction employing a small clearance 30 space, thus making high compressions easily obtainable, and insuring an economy of fuel. Another objection to the puppet valve type of motor is that the valve area is relatively small, and further the opening 35 and closing movements of the valves and the admission of the working fluid are not as rapid as desirable, particularly at high speeds. The construction of my engine has made feasible a most convenient arrangement 40 of parts so that the various mechanisms are instantly accessible.

It is an object of this invention to provide a construction affording an operator an opportunity to instantly examine the operating 45 gear without the necessity of exploring the crank pit as in case of great emergency when used in the air, on land and at sea.

It is also an object of this invention to construct an internal combustion engine 50 wherein inlet and exhaust ports are provided at the upper end of each of the cylinders thereof and are controlled by means of sleeves slidably mounted within said cylinders

ders, the respective inlet and exhaust sleeves moving independently of one another. 55

It is also an object of this invention to construct an internal combustion sleeve valve engine wherein each of the respective sleeves are slidably mounted within the engine cylinders independently of one another and the engine piston, so that wear between the respective sleeves and the piston is obviated.

It is also an object of this invention to construct an internal combustion engine provided with inlet and exhaust sleeve valves 65 mounted within each of the engine cylinders and operable independently of, and out of contact with, one another by means of suitable cam mechanisms connected to be driven from the crank shaft of the engine. 70

It is also an important object of this invention to construct an internal combustion sleeve valve engine wherein an improved oiling mechanism is provided for introducing oil around the sleeve valves. 75

It is also an object of this invention to construct an internal combustion engine provided with sleeve valves operating independently of, and out of contact with, one another by means of valve rods, one slidable 80 within the other and each suitably and independently actuated.

It is also an object of this invention to construct an internal combustion engine wherein sleeve valves are mounted to control the respective inlet and outlet ports at the upper ends of the cylinders of the engine, and with water jackets disposed around the cylinders also surrounding the respective inlet and exhaust ports acting to 90 maintain practically all parts of the engine at a constant temperature.

It is also an object of this invention to construct an internal combustion engine wherein independent sleeve valves are 95 mounted to control the respective inlet and exhaust ports at the upper ends of each of the cylinders, each of said sleeve valves being provided with a central actuating rod, the rod of one valve extending through that of 100 the other, and each of said rods operated from suitable means.

It is a further object of this invention to construct an improved type of internal combustion engine wherein the inlet and exhaust ports communicate directly through

the walls of the engine cylinders and are controlled by independently movable sleeve valves operating out of contact with one another and the piston in the cylinder.

It is finally an object of this invention to construct an internal combustion engine wherein noise is almost entirely obviated and economy in operation is secured, due to the use of sleeve valves mounted directly in the heads of the engine cylinders in a manner permitting a small clearance space to be attained.

The invention (in a preferred form) is illustrated in the drawings and hereinafter more fully described.

In the drawings:

Figure 1 is a conventional side elevation partly broken away and shown in section of an engine embodying the principles of my invention.

Fig. 2 is a top plan view thereof with the cover for the valve gearing removed.

Fig. 3 is a transverse vertical section taken on line 3-3 of Fig. 2.

Fig. 4 is an enlarged fragmentary detail with parts in section and parts in elevation similar to Fig. 3, but illustrating the upper portion of one cylinder of the engine.

Fig. 5 is a fragmentary detail view showing in section the upper end of one of the engine cylinders.

Fig. 6 is a detail section with parts omitted taken on line 6-6 of Fig. 3.

Fig. 7 is a detail section with parts omitted taken on line 7-7 of Fig. 3.

Fig. 8 is a fragmentary detail section taken on line 8-8 of Fig. 6.

Fig. 9 is a fragmentary side view of the mechanism illustrated in Fig. 4.

Fig. 10 is a transverse section taken through one of the cams.

Fig. 11 is a horizontal section taken through one of the inlet sleeve valve members.

Fig. 12 is a detail partly in section.

As shown in the drawings:

The engine embraces a crank case 1, the lower portion 2, of which is removably bolted thereto, and with bearing members 3, integrally connected by means of webs 4, to the walls of the upper portion 1, of the crank case. The cylinders in the present instance denoted by the reference characters A, B, C, and D, are preferably cast *en bloc* for compactness, although not necessarily so, and around the walls 5, of each of the cylinders, the casting is cored to afford a water jacket 6, which extends around and over the upper portion of the cylinders. A crank shaft 7, is journaled in the bearings in said crank case, and is suitably connected by means of connecting rods 8, to trunk pistons 9, one mounted in each of the respective cylinders of the engine.

Inlet and exhaust ports, denoted respectively by the reference numerals 10 and 11, extend peripherally around the cylinders at the upper end of each thereof except for a small web portion on diametrically opposite sides, one of said web portions being clearly shown in Fig. 5, and both being shown clearly in Figs. 1, 6, and 7. Between the walls of the water jacket 6, and the walls 5, of the cylinders proper, annular passages 12 and 13, respectively, are cored within the casting, the former communicating with the inlet ports 10, of a cylinder, and the latter with the exhaust ports 11, thereof. On each of the cylinders of the engine an inlet 14, is formed through the wall 6, of the water jacket communicating with the annular inlet fuel passage 12, and similarly an outlet 15, is formed through the opposite wall of the water jacket communicating with the exhaust passage 13. An intake manifold 16, is suitably connected upon the outer walls 6, of the engine with the respective outlets from the manifold registering with the inlets 14, leading to the inlet passages of the cylinders. Similarly an exhaust manifold 17, is mounted on the opposite side of the engine, the respective inlets to the manifold communicating and registering with the outlet apertures 15, from the exhaust passages of the engine.

The firing of a charge of fuel introduced into the cylinders is effected by means of a spark plug 18, threaded into and through the top wall of each of the cylinders and at one side thereof. The valve members controlling the respective inlet ports 10, and exhaust ports 11, in each of the cylinders, are independent of one another and each similarly constructed, the inlet valve consisting of a ring 19, integral with a hollow hub 20, and connected thereto by hollow radial arms 21, which communicate into the hollow hub 20, to receive oil therefrom and pass the same to the outer periphery of the ring. A piston ring or packing 22, is recessed into the outer peripheral surface of the valve ring to insure a sealing fit thereof over the inlet ports 10.

A tubular valve rod 23, is integrally connected on the hub portion 20, of the valve and extends upwardly through the upper wall of the engine through a suitable packing gland 24. An oil passage 25, is formed within the walls of said tubular valve rod, said passage at its lower end communicating laterally with a passage in a cross head 26, secured on the upper end of the valve rod and supporting an oil cup 27, thereon in a manner to feed oil into the oil passage.

The valve for the exhaust ports 11, is similarly constructed, and is denoted as a whole by the reference numeral 28. In the latter instance, however, the tubular valve

rod 29, is not integral with the hub portion of the valve, but is threaded therein, and is provided with laterally directed passages which communicate with the interior of the 5 hollow hub portion of the valve. Said tubular valve rod 29, extends slidably through said valve rod 23, of the inlet valve, so that relative movement may take place between said respective valve rods independently of 10 one another. A cross head 30, is threaded on the upper end of the exhaust valve rod 29, and is provided with an integral lateral extension 31, which supports an oil cup 32, the oil from said cup passing through a suitable 15 interior passage in said arm 31, to the tubular valve rod 29, where it then flows downwardly and into the valve 28. Of course, any conventional type of check valves may be mounted in the oil lines of 20 each of the valves to prevent a reverse flow taking place therethrough, but for convenience of illustration such valves have not been shown. A gudgeon pin 33, extends through said cross head 30, and serves to 25 pivotally connect thereto the pair of links 34, which, at their upper ends, are connected by means of another gudgeon pin 35, to one arm 36, of a bell crank. A number of supporting brackets 37, two 30 on each cylinder, are mounted on the upper or top wall of the engine, and extending therethrough is a shaft 38, on which said bell cranks for operating the exhaust valves of the cylinders are pivoted. A cam shaft 39, journaled in bearings at 35 each of its ends, is positioned slightly below at one side and parallel to said shaft 38, above the cylinders of the engine, and is suitably driven from the crank shaft 7, by 40 means of a chain or link belt 40. A housing 41, is provided to inclose the cam shaft driving mechanisms to protect the same from dust and to deaden the noise of operation thereof. A plurality of cams 42, are rigidly secured upon said cam shaft 39, one cam for 45 each cylinder of the engine, each running in a bath of oil, and, as clearly shown in Fig. 10, each of said cams is provided with continuous grooves or slots 43 and 44, respectively, on opposite faces thereof, the groove 43, being for the inlet valve, and the groove 44, for the exhaust valve. Accordingly, in 50 order to operate the exhaust valve, said bell crank, having the arm 36, is provided with another arm 45, which, at its ends has a roller which engages in the groove 44, of the cam. Said cross head 26, on the valve rod for the inlet valve, is provided with 55 gudgeon extensions 46, upon which are pivotally engaged a pair of links 47, which, at their upper ends, are connected to one arm 48, of a bell crank by means of a pin 49. Said bell crank is also pivotally mounted 60 upon said shaft 38, alongside of the bell 65

crank for the exhaust valve, and is provided with another arm 50, which, at its end, is provided with a roller tracking in the groove 43, of the cam. As clearly shown in Fig. 1, the annular outlet passages for each 70 of the cylinders are larger than the annular inlet passages 13, and this, of course, is to permit ready egress of the burnt gases with as little back pressure as possible. 75

The operation is as follows: The cam shaft 39, is driven by a one to two drive from the crank shaft 7, of the engine, so that the number of reciprocations of the respective annular inlet and exhaust valves within the cylinders are only 80 half as great as that of the pistons. Of course the respective cam grooves 43 and 44, in the cams 42, are formed so as to open and close the respective inlet and exhaust ports of the cylinders to insure the proper cycle 85 of operation of a four stroke cycle taking place. Not only is a quick but an exceedingly large port area opening afforded for either the intake or ejection of the gases when the sleeve valves are moved, but the 90 particular arrangement of the parts, that is to say with the valves in the heads of the cylinders proper and the annular inlet and exhaust passages cored around the cylinders within the water jacket thereof, insures an even temperature of all the working parts of the engine, a pre-heating of the inflowing fuel, and a cooling of the exhaust. 95 The valve gearing mounted on the top of the engine, is of course duplicated for each of 100 the cylinders, and as a whole is a very simple mechanism, and due to the fact that an oil supply is carried upon the respective parts of the inlet valve and exhaust valve gearing, a positive oil feed directly to the walls of 105 the cylinders of the engine for the valves is insured. In order to inclose said valve mechanisms from dust and to deaden what little noise of operation there is in this portion of the mechanism, a large cover 51, is 110 connected by means of hinges 52, to the top wall of the engine and closes over all of said valve gearing, and when access to any part thereof is desired, said cover may be 115 easily swung back.

Due to the fact that I use cams provided with cam grooves, the actuating mechanisms for the respective valves are positively moved or reciprocated in both directions, thus obviating the use of springs, and inasmuch as the extent or amplitude of movement of the respective valves in the cylinders is relatively small, the use of a positively actuated mechanism is entirely feasible, whereas in a puppet valve engine such 125 an attempt to omit the use of springs would not be practical, as the movement which is demanded is much greater and would be too slow.

There are a number of details of this in- 130

vention which may be varied through a wide range without departing from the principles thereof. I therefore do not purpose limiting the patent granted otherwise than necessitated by the prior art.

I claim as my invention:

1. In a device of the class described an internal combustion engine comprising a cylinder having inlet and exhaust ports in the walls thereof, a piston in the cylinder, a pair of sleeve valves slidably mounted to move along the walls within the cylinder above the piston to control the opening and closing movement of said inlet and exhaust ports, and means connected to each of said sleeve valves to operate the same independently and out of contact with one another and with said piston.
2. In a device of the class described an internal combustion engine comprising a cylinder having inlet and outlet ports in the walls thereof, a piston movable in said cylinder, a plurality of sleeve valves movable within said cylinder along the walls thereof to control the opening and closing of said inlet and outlet ports, and mechanism for operating said sleeve valves, said sleeve valves and piston all operating in proper sequence and out of contact with one another at all times.
3. An internal combustion engine of the class described, a cylinder, a piston therein, inlet and exhaust ports formed in the cylinder walls at the upper end thereof, sleeve valves movable along the cylinder walls independently and out of contact with one another within the upper end of said cylinder, a valve rod for moving one of said valves and a valve rod connected to the other of said sleeve valves and extending through said first mentioned valve rod.
4. In a device of the class described a cylinder, a pair of slide valves mounted in the upper end thereof to control the inlet and exhaust of the cylinders, valve rods for actuating said valves, the valve rod of one valve moving slidably within the valve rod of the other valve, mechanism for actuating said valve rods, and means introducing oil into the cylinder through said valve rods and through said valves.
5. An engine of the class described comprising a cylinder, a plurality of valves in said cylinder controlling the inlet and exhaust thereof, said valves moving independently and out of contact with one another, valve rods, one for each of said valves, the valve rod of one valve extending slidably through the valve rod of the other valve, and means introducing oil into the cylinder through said valve rods and valves.
6. In a device of the class described an engine comprising a cylinder, a piston movable therein, a crankshaft driven by said piston, a pair of slide valves mounted within

the cylinder in contact with the walls thereof at the upper end of said cylinder, said valves movable independently and out of contact with one another and with said piston, valve gearing mounted on top of the engine, and driving connections between said crankshaft and said valve gearing for operating the slide valves at proper intervals of time.

7. In a device of the class described an internal combustion engine comprising a cylinder, a piston movable therein, a connecting rod connected to said piston, a crankshaft driven by said connecting rod, valve gearing mounted on the top of the engine and connected to be driven from the crankshaft of the engine, and slide valve mechanism mounted within said cylinder comprising sleeves, one disposed above the other and out of contact with said piston and each other, said valve mechanism actuated by said valve gearing to control the inlet and exhaust of the cylinder.

8. In an engine of the class described a cylinder, a piston movable therein, inlet and exhaust ports in the upper end of said cylinder, annular valves slidably mounted within said cylinder in contact with the inner walls thereof and disposed above said piston to control the flow through said ports, and actuating mechanisms for said valves, the actuating mechanism of one valve extending slidably through that of the other.

9. In a device of the class described an internal combustion engine, valves therein controlling the inlet and exhaust thereof, mechanism for operating said valves, the mechanism of one valve extending slidably through that of the other, and means introducing lubricating fluid through each of said mechanisms.

10. In an internal combustion engine slide valves controlling the inlet and exhaust thereof, and operating independently and out of contact with one another, and means introducing lubricating fluid to the cylinders of the engine through said valves.

11. In an engine of the class described the combination with a cylinder and a piston movable therein, said cylinder having inlet and exhaust ports in the walls thereof, of valves mounted within the cylinder in contact with the walls thereof and out of contact with one another, said valves connected for synchronous operation with said piston, and constructed to introduce lubricant into the cylinder.

12. In an engine of the class described the combination with a cylinder and piston movable therein, of reciprocative sleeve valves movable within the cylinder, mechanism for operating the same from the exterior of the cylinder, and means introducing lubricant into the cylinder through said mechanism and said sleeves.

13. In an engine of the class described the combination with a cylinder and piston movable therein, of sleeve valves movable independently of one another in contact with 5 the walls of the cylinder and out of contact with one another, inlet and outlet ports in the walls of said cylinder controlled by sleeve valves, and a water jacket formed around said cylinder and between the respective inlet and outlet ports thereof.
14. In an engine of the class described a cylinder, a piston movable therein, sleeve valves mounted within said cylinder movable over the inner walls thereof and disposed at one end of the cylinder out of contact with the piston, and independently operating slidably interfitting actuating means 15 for said valves connected centrally thereto and extending through the end of the cylinder.
15. In an engine of the class described a cylinder, a piston movable therein, said cylinder having inlet and outlet peripheral ports in the walls thereof, a water jacket formed around said cylinder, inlet and outlet passages formed between said cylinder walls and said water jacket communicating with said respective ports, and sleeve valves mounted within said cylinder out of contact with 20 one another and out of contact with
16. In an engine of the class described a cylinder, a piston movable therein, inlet and outlet peripherally disposed ports at 35 one end of said cylinder above the limit of upper travel of said piston, sleeve valves mounted within said cylinder movable over the walls thereof out of contact with one another and out of contact with said piston 40 to control the flow through said inlet and outlet ports, inlet and outlet passages cored around the exterior of the cylinder walls communicating with said ports, a water jacket formed integral with said cylinder 45 and inclosing the same and said inlet and outlet passages whereby the circulation of water may be maintained therearound and therebetween, and means centrally connected to said sleeve valves and extending through 50 one end of the cylinder for independent operation of said sleeve valves.

In testimony whereof I have hereunto subscribed my name in the presence of two subscribing witnesses.

HENRIK C. STRÄNG.
